 tion of New Jersey

Application March 1, 1939, Serial No. 259,292

13 Claims. (Cl. 34—135)

This invention relates to apparatus for cooling, or otherwise treating, material in rotary drums by gaseous fluids.

More particularly, it relates to that type of apparatus in which the material passes longitudinally through the drum, and the gaseous fluid, such as air, is introduced from a wind-box through openings in the shell of the drum, first to compartments at the interior surface of the shell and thence through the material, the gaseous fluid being introduced principally through those shell openings which at the time lie under the material in the drum.

In accordance with one phase of our invention the wind-box is supported solely by the rotary shell of the drum preferably by means of wheels associated with the wind-box which operate on a track carried by the shell, the wind-box being held relatively stationary as the shell rotates within it. So far as this feature of the invention is concerned the wind-box preferably completely encircles the shell of the drum, but so far as other features of the invention are concerned it is immaterial whether it extends entirely around the shell of the drum or not.

The discharge outlet of the wind-box faces the drum shell, and the openings through the shell move directly under the wind-box and over its discharge outlet. The shell openings are so positioned that when the air compartments within the shell are arranged in two circumferential rows, each shell opening lies partly to one side of the partition which separates the rows of air compartments and partly to the other side thereof, so that the air admitted through the shell openings will be divided and part will pass to the air compartments at one side of the partition while the rest will pass to the air compartments at its opposite side. Preferably, a hood is placed within the shell over each shell opening to prevent solid material from passing outwardly into the wind-box, and an adjustable plate is associated with the hood to change, when desired, the proportion of air admitted to the two rows of air compartments.

A barrier is positioned in the wind-box at either side of the place where air is admitted to it. Each barrier completely spans the passage through the wind-box and is adjustable circumferentially of it to adjust not only the circumferential length of the discharge outlet of the wind-box, but also the circumferential length of the portion of the wind-box to which the air is admitted. Air is thus caused to flow principally through those shell openings which at the time

are opposite that portion of the wind-box which lies between the two barriers, the arrangement being such that these particular shell openings are the ones which lie under the material within the drum. Each barrier is provided with a regulable opening to permit a small amount of air to pass by it into the portion of the wind-box beyond the barrier to cool the cover plates of the air compartments which lie above the level of the material in the drum.

The cover plates for the air compartments are curved or inclined so that the trailing edge of one cover plate will overlap the leading edge of the succeeding one to provide suitable slot-like openings through which air passes from the air compartments into the material within the drum. Each of the cover plates is secured at its center portion only to the shell of the drum.

The invention includes certain other improvements hereinafter described.

Our improved apparatus was designed especially for use in cooling cement clinker by means of air, but it may be used for other purposes, and with a gaseous fluid other than air, and even for heating or chemically treating material rather than cooling it. However, for convenience the apparatus will hereinafter be designated a cooler and the gaseous fluid will be referred to only as air.

30 In the accompanying drawings the improvements are illustrated in connection with the cooling section of a rotary tubular kiln, but it will be understood that the improvements are applicable to a cooler that is separate and distinct from the kiln.

In the drawings:

Figure 1 is a transverse vertical section through the improved cooler the section being taken on the line 1—1 of Fig. 3;

40 Fig. 2 is a side elevation of the portion of the cooler shown in Fig. 1;

Fig. 3 is a vertical longitudinal section through the cooler taken on the line 3—3 of Fig. 1;

Fig. 4 is a transverse section taken on the line 4—4 of Fig. 3 illustrating the manner in which the cover plates for the air compartments are mounted;

Fig. 5 is a longitudinal section through one of the barrier blocks employed in the wind-box;

Fig. 6 is an end view of the barrier block shown in Fig. 5;

Fig. 7 is an enlarged view of the upper portion of Fig. 3 with more of the parts shown in cross section;

55 Fig. 8 is a transverse section through the wind-

box taken on the line 8—8 of Fig. 1 with the barrier blocks omitted;

Fig. 9 is a section taken on the line 8—8 of Fig. 7 illustrating the means for adjusting the wheeled shafts that carry the wind-box;

Fig. 10 is an end view of half of the cage that fits into the drum shell and forms the walls of the air compartments, this view also showing several sections of the sectional discharge ring;

Fig. 11 is a plan view of a portion of the cage as viewed outwardly from its central axis;

Fig. 12 is a longitudinal section through the cage taken on the line 12—12 of Fig. 11;

Fig. 13 is a longitudinal section through the cage taken on the line 13—13 of Fig. 11;

Fig. 14 is a side elevation of a portion of one of the sectional air-seal rings for the wind-box;

Fig. 15 is a transverse section taken on the line 15—15 of Fig. 14; and

Fig. 16 is a detail view illustrating the manner in which an air seal is effected at the adjoining ends of two sections of the air-seal ring shown in Fig. 14.

As above stated the improved cooler may be an independent one but in the drawings it is illustrated in connection with a rotary kiln of the drum type. The shell of the kiln is shown at 1 (Fig. 3) and has the usual lining 2. The shell is mounted to rotate about an axis which is slightly inclined to the horizontal so that the material in the kiln, such as cement clinker, feeds towards its lower discharge end as the kiln rotates. In the present instance the shell 3 of the cooler forms a continuation of the shell 1 of the kiln.

The shell of the cooler is provided with an external reinforcing band 4 (Figs. 3 and 7) preferably welded in place. A pair of flanges 5 are welded edgewise to the reinforcing band and to each of these flanges is secured one rail 6 of a track. Two pairs of wheels 7 (Figs. 1, 3 and 7) are mounted to operate on the track formed by the rails 6. Each pair of wheels is mounted on a shaft 8. The two shafts 8 support an annular wind-box preferably formed by fastening together two side plates 9 and 10 (Fig. 7) and an outer plate 11. The wind-box is thus channel-shaped in cross section with the opening 12 of the channel facing the shell 3 of the cooler. At spaced intervals within the wind-box are stiffening ribs 11' provided with openings 11" through which the air may pass. The annular wind-box thus formed is supported from the shafts 8 by bearings 13 so that the wind-box is accommodated in the space between the two rails 6 of the track.

The wind-box preferably completely encircles the shell of the cooler, as best shown in Fig. 1, but so far as some of the features of the invention are concerned the wind-box may extend only partly around the cooler shell. When the wind-box completely encircles the cooler shell it is preferably formed in at least two sections for convenience in assembling. The sections may be bolted together at the flanges 14 and 15 (Fig. 1).

The lower portion of the wind-box is connected to an elbow 16 forming part of an air conduit to which air is supplied by means of a fan 17, or in any other suitable way. The junction of the elbow 16 and the wind-box thus constitutes the air inlet for the wind-box.

The major portion of the air leaving the wind-box through its discharge opening 12 passes through certain openings provided in the shell of

the cooler, as hereinafter described, but it will be noted from Fig. 7 that some of the air may pass laterally under the inner edges of the wind-box plates 9 and 10 and would escape to the outside atmosphere if not prevented from doing so. We, therefore, provide an air-seal between the wind-box plates 9 and 10 and the corresponding track rails 6. The air-seal between the plate 10 and the corresponding track rail 6 may comprise a sectional ring 18, the sections of which are bolted to a machined surface 19 on the plate 10 by means of bolts 20. The outer face of the sectional ring 18 bears directly against the track rail 6. Figs. 14, 15 and 16 show the details of this sectional ring. There is a slight clearance between the ends of the ring sections, as shown in Figs. 14 and 16, through which air is prevented from leaking by means of a spring 21 (Fig. 16) positioned in longitudinal slots 22 at the joining ends of the ring sections.

A similar sectional air-seal ring 23 bears against the other track rail 6. In this case, however, it is clamped to the inner edge of a diaphragm 24 by means of a sectional clamping ring 25. The outer edge of the diaphragm 24 is clamped by means of a sectional clamping ring 26 to a flange 27 carried by the outer plate 11 of the wind-box. In addition to a number of cap screws which clamp the ring 25 to the ring 23 there are some special screws 28 which have inwardly projecting cylindrical heads 29 (Fig. 7) surrounding each of which is a helical spring 30. The springs 30 react against a machined surface 31 on the side plate 9 of the wind-box. It will thus be seen that the springs 30 force the sealing ring 23 against its corresponding track rail 6 and at the same time force the opposite sealing ring 18 against its corresponding track rail 6. When the track formed by the rails 6 rotates with the cooler shell, the sealing rings 18 and 23 being carried by the wind-box and thus held stationary, make sliding contact with the inner faces of the track rails and thus together with the diaphragm 24 prevent any of the air that leaves the wind-box from passing to the outside atmosphere. Lubricant may be supplied to the bearing faces of the sealing rings 18 and 23 by pipes 18' and 23', as best shown in Figs. 8 and 15.

It will be noted that the wind-box is supported solely by the rotary shell of the cooler, the track and the wheels providing anti-friction means for accomplishing this. The wind-box remains stationary while the cooler shell rotates within it. To hold the wind-box stationary as the cooler shell rotates and to adjust its position circumferentially of the shell when necessary, the turn buckle shown in Fig. 1 is employed. This may comprise right and left hand eyebolts 32 and 33 threaded into a long sleeve 34 and locked in position by lock nuts 35 and 36. The upper eyebolt 32 is connected to a bracket 37 carried by the wind-box and the lower eyebolt 33 is connected to some fixed point, such as the floor, as shown at 38. The sleeve 34 is provided with holes 39 by means of which the sleeve may be turned with a drift pin. It is obvious that by loosening the lock nuts 35 and 36 and by turning the sleeve 34 the wind-box may be moved a limited distance in either direction circumferentially about the shell of the cooler after which the lock nuts 35 and 36 may be tightened to hold the wind-box in fixed position. To permit this movement of the wind-box the air conduit between

the elbow 16 and the fan 17 has a section made up of telescopic parts 39 and 40, the telescopic joint of which may be sealed by a wrapping indicated at 41. The telescopic part of the conduit is connected to the elbow 16 by a connecting portion 42 and to the fan 17 by a connecting portion 43. The joints between these connecting portions and the telescopic part of the conduit are loose ones as indicated at 44 and 45 so that the several portions of the conduit will adjust themselves to the new position of the wind-box. These loose joints may be provided with a suitable wrapping 46 to prevent air leakage.

Each shaft 8, in addition to being mounted in the bearing 13, is guided by two forked brackets 47 and 48 (Figs. 7 and 9) which are bolted respectively to the flange 27 at one side of the wind-box and to an extension 49 on the side plate 10 at the other side of the wind-box. Where the shaft 8 passes between the arms of 20 the brackets 47 and 48 it is provided with machined surfaces 50 (Fig. 9) on which rectangular washers 51 fit. Each washer 51 is provided with a slot 52 which engages with the bracket to prevent the washer from turning. The washers are 25 also provided with holes into which the inner end of adjusting screws 53 are fitted, these adjusting screws being mounted in the forks of the bracket. By adjusting the screws 53 the shafts 8, and the wheels carried by them, may be slightly adjusted to cause the wheels to run true on the track rails 6. This adjustment of the shafts 8 is permitted by the nature of the bearings 13. After each shaft is adjusted by the screws 53 a slight clearance is left between the washers 51 and the machined surfaces 50 on the shaft to permit the shaft to swing slightly (in the plane of the drawing). The bearings 13 are of such a nature as to permit this movement of the shafts. Any irregularities in the track and the shell are thus compensated for thereby causing the annular wind-box to ride properly on the track following the motions of the shell. The shell may thus freely rotate within the annular wind-box without disturbing its proper alignment.

The shell 3 of the cooler is provided with a series of openings 54 (which also pass through the reinforcing band 4) which move directly under the discharge opening 12 of the wind-box. The air passing through these openings into the cooler first enters air compartments positioned at the interior surface of the shell and which will now be described.

The side walls of the air compartments are formed by a cage which is assembled as shown in Figs. 10-13. The cage comprises longitudinal partitions 55 and end circumferential partitions 56 and 57. As we prefer to have two circumferential rows of air compartments instead of one, there is provided an intermediate partition 58 so positioned longitudinally of the shell that to the right of this partition, as viewed in Figs. 11-13, there is one circumferential row of relatively long air compartments, and to the left of this partition another circumferential row of relatively short air compartments. The longitudinal and circumferential partitions may be suitably interconnected by means of brackets 59 and splice plates 59a. Circumferential straps 59' and 59'' are provided which are made up of sections welded to the splice plates 59a secured to the longitudinal partitions. The cage is bolted to the shell by means of brackets 60.

Each of the shorter air compartments has one cover plate and each of the longer air compart-

ments has two of such cover plates arranged end to end. These cover plates are shown at 61. Each of them is fastened in place by means positioned at its center portion only. For this purpose each of the cover plates is provided with a square hollow boss 62 located at its center into which projects the eye of an eyebolt 63. A pin 64 passes transversely through the walls of the boss 62 and through the eye in the eyebolt. The boss 62 rests upon a supporting block or pedestal 65 which is bolted to the shell as shown at 66 (Fig. 4). The upper portion of the supporting block 65 is provided with longitudinal ribs 67 between which the square boss on the cover plate fits so as to prevent the cover plate from turning. The shank of the eyebolt 63 passes through a central opening 68 in the pedestal 65 and projects through the shell 3 where a nut 69 is threaded on its extremity and thereby clamps the cover plate to the pedestal.

Each cover plate 61 is inclined or curved from its leading edge 61a to its trailing edge 61b toward the axis of the cooler (Fig. 4). The trailing edge 61b of each plate slightly overlaps the leading edge of 61a of the succeeding plate so as to form a slot-like opening 70 through which air may escape from the air compartment under the cover plate into the interior of the cooler where it passes through the material therein, as hereinafter described. The cover plates may, if desired, be provided with openings or slots 71 through which air may also pass from the air compartments into the interior of the cooler. The cover plates are also preferably provided with strengthening ribs 72. The adjoining ends 30 of the cover plates 61 lie over the circumferential straps 59 and 59''.

A sectional discharge ring 86, bolted to the shell 3 as shown at 87, insures that a certain layer of material will remain on the cover plates 61 during the operation of the apparatus.

It will be noted from Figs. 3 and 7 that the plane of the intermediate circumferential partition 58 intersects each of the openings 54 in the cooler shell. In other words, one part of each of the openings 54 lies to one side of this partition while the remaining part lies to the other side of the partition. Thus the air entering the air compartments through the openings 54 would normally be divided so that part would flow to the short air compartments on one side of the partition and part would flow to the longer air compartments on the other side of the partition. However, over each opening 54 there is a hood 73 (best shown in Fig. 7) which interrupts the continuity of the partition 58. These hoods are part of the cage as shown in Figs. 11 and 12 and are welded in place when the cage is assembled. Inside of each hood there is a plate 74 adjustably attached to the cover 75 of the hood by means of the bolt 76. At either side of the plate 74 the hood is provided with an opening 77. Thus the air entering the air compartments first passes through this hood and is divided by the plate 74 so that part of it passes through one hood opening 77 to the shorter air compartments while the rest passes through the other hood opening 77 to the longer air compartments. By adjusting the position of the plate 74 the proportion of air supplied to the two circumferential rows of air compartments may be changed. The hoods substantially prevent any solid material which gets in the air compartments from passing out into the wind-box while they permit free ingress of air from the wind-box into the air compartments.

Mounted within the annular wind-box at either side of the air inlet is a hollow barrier block 78 (Figs. 1 and 5). These barriers completely span the passage through the wind-box and therefore determine by their position the circumferential length of that portion of the wind-box to which air is admitted. In other words, they do not merely adjust the circumferential length of the discharge opening 12 of the wind-box but they also adjust the circumferential length or volume of the effective part of the wind-box. Each barrier block may be adjusted circumferentially of the wind-box by means of a cap screw 79 which projects through a slot 80 (Fig. 2) in the outer wall 11 of the wind-box. A washer 81 prevents the escape of air through this slot. By loosening the cap screw 79 each barrier block may be adjusted a limited amount circumferentially of the wind-box and is held in adjusted position when the cap nut is tightened. It is obvious that the distance between the two barrier blocks 78 will determine the number of openings 54 in the cooler shell through which air is permitted to pass at any one time into the interior of the cooler. In other words, direct air supply is substantially cut off to all of the openings 54 except those which are passing between the barrier blocks. During rotation of the cooler (in the direction of the arrow shown in Fig. 1) the material indicated at M occupies a position somewhat as indicated in this figure, and the barrier blocks 78 are so positioned that the air will pass through those openings 54 which lie under the material when the cooler is rotating. It is desirable to let a small amount of air pass by the barrier blocks and into the portion of the wind-box beyond them so that it may cool the cover plates 61 that happen to be above the level of the material. For this purpose the transverse wall of each barrier block is provided with an opening 82 (Figs. 5 and 6) which is controlled by a disc 83 threaded on a stem 84. By turning the disc 83 it may be moved toward or away from the opening 82 and it therefore acts as an adjustable valve to regulate the amount of air permitted to pass through the opening 82.

Projecting outwardly from the side wall 9 of the wind-box are two partitions 85, one of which is shown in Fig. 8. One of these partitions is located near one barrier block 78 and the other one is located near the other barrier block, as indicated by the dotted lines in Fig. 1. The purpose of these partitions is to prevent the air which leaks around the inner edge of the wall 9, within the space bounded by the barrier blocks 78, from passing too freely into the rest of the annular wind-box.

When the annular wind-box has been adjusted to its proper circumferential position by turning the sleeve 34 of the turn buckle, and has been locked in proper position by the lock nuts 35 and 36, and when the barrier blocks 78 have been adjusted to their proper positions to permit air to flow through the desired number of openings in the shell, and when the adjusting plates 74 in the hoods 73 have been properly set, the apparatus is ready to operate. Air from the fan 17 passes into the annular wind-box and then through the openings 54 which are in the zone between the two barrier blocks 78, and into the corresponding air compartments. If there is only one circumferential row of air compartments all of the air passing through one of the openings 54 passes into the air compartment with which that opening communicates. On the other

hand, if there are two circumferential rows of air compartments, as shown in the drawing, the air passing through each shell opening 54 is divided by the plate 74 in the hood which covers that opening so that part of the air passes into the air compartment at one side of the circumferential partition 58 while the rest of the air passes into the air compartment at the opposite side of this partition. The adjustment of the plate 74 will determine the proportion in which the air is admitted to the two compartments at opposite sides of the partition. In some cases it may be desirable to supply a large quantity of air to the circumferential row of compartments over which the material first passes upon leaving the kiln so as to produce a sudden air quenching of the hot material, and to supply a smaller quantity of air to the other row of compartments over which the material later passes to effect a slower cooling of the material in this part of the cooler. However, there may be other reasons for changing the distribution of air to the compartments of the two rows, or as above stated there may be only one circumferential row of air compartments in which case there would be no division of the air at all. Moreover, when two circumferential rows of air compartments are employed the compartments at opposite sides of the partition 58 may be of the same length, if so desired.

The air leaves the air compartments through the openings 71 in the cover plates and through the slot-like openings 70 formed between the overlapping edges of the plates and passes into 35 and through the bed of material feeding through the cooler.

There is no contact between the rotating shell and the annular wind-box except at the sealing rings 18 and 23, and there is no wear which 40 might eventually change the adjustment of the passages, nor can any inaccuracies in the shell structure, caused for instance by warping due to heat, result in any change in the amount of air which passes through the bed of material.

45 While we have referred throughout the specification and claims to the use of air as the cooling medium, some other gaseous fluid may be used especially if the material to be treated is affected by oxygen.

50 It is to be understood that no limitation is intended where the claims refer to the gaseous fluid as "air," since this term is used simply for convenience to mean any gaseous fluid whether a cooling fluid, a heating one, or one which affects a chemical treatment of the material.

We claim:

1. The combination of a cylindrical shell rotatable about a generally horizontal axis, a relatively stationary annular wind-box encircling the shell, means for admitting air from the wind-box through the shell into the interior of the shell, and anti-friction means operatively interposed between the shell and wind-box, the shell acting through said anti-friction means to provide the sole support for the wind-box.

2. The combination of a cylindrical shell rotatable about a generally horizontal axis, a relatively stationary annular wind-box encircling the shell, means for supporting the wind-box solely 70 by the shell comprising a track mounted on one of said parts and wheels mounted on the other of said parts and running on the track, and means for admitting air from the wind-box through the shell into the interior of the same.

75 3. The combination of a cylindrical shell ro-

tatable about a generally horizontal axis, a track carried by and encircling said shell, wheels operating on said track, an annular wind-box encircling said shell and supported by said wheels on said track, means for holding the wind-box stationary as the shell rotates, and means for admitting air from the wind-box through the shell into the interior of the same.

4. The combination of a cylindrical shell rotatable about a generally horizontal axis, a pair of track rails carried by and encircling said shell, at least one pair of wheels operating on the track, a shaft on which said wheels are mounted, an annular wind-box encircling said shell and located between said track rails and supported from said shaft, means for holding the wind-box stationary as the shell rotates, and means for admitting air from the wind-box through the shell into the interior of the same.

5. The combination of a rotatable cylindrical shell, a relatively stationary wind-box at least partly encircling the shell and having a circumferentially elongated discharge opening, the shell having a series of openings adapted to communicate with said discharge opening and through which air may pass from the wind-box into the interior of the shell, an air inlet for the wind-box, means interposed between the wind-box and shell through which the shell acts to provide the sole support for the wind-box, and means connected to the wind-box and to a fixed point and operable for adjusting the wind-box circumferentially of the shell.

6. The combination of a rotatable cylindrical shell, a relatively stationary wind-box at least partly encircling the shell and having spaced side walls and a circumferentially elongated discharge opening in its side facing the shell, the shell having a series of openings lying between the side walls of the wind-box and registering successively with said discharge opening as the shell rotates to permit air from the wind-box to pass into the interior of the shell, an air inlet for the wind-box, and a barrier within the wind-box at either side of said air inlet completely spanning the passage through the wind-box and adjustable circumferentially of the wind-box whereby the circumferential length of the portion of the wind-box to which air is admitted by said inlet may be adjusted.

7. The combination of a rotatable cylindrical shell, means at the interior surface of a portion of the shell forming two circumferential rows of air compartments, a circumferential partition separating the compartments of the two rows, said shell having a circumferential series of openings so positioned that one part of each opening lies to one side of said partition and the remaining part lies to the other side of the partition, and a relatively stationary wind-box at least partly encircling the shell and having a discharge opening facing the shell, said shell openings coming successively into registry with said discharge opening as the shell rotates whereby air discharged from the wind-box through the shell openings and into said air compartments is divided by said partition and part passes into the air compartments of the row at one side of the partition while the other part of the air passes into the air compartments of the row at the opposite side of the partition.

8. The combination of a cylindrical shell rotatable about a generally horizontal axis, means at the interior surface of a portion of the shell forming at least one circumferential row of air

compartments, said shell having a series of openings each of which communicates with one of said air compartments, a relatively stationary wind-box at least partly encircling the shell and having a discharge opening adapted to communicate with said shell openings, and a hood within said compartment at each shell opening for substantially preventing passage of solid material from the compartment into the wind-box while permitting air from the wind-box to enter the compartment, said hood including a part extending inward from the wall of the shell around the shell opening and having an air opening and another part spaced from the shell wall and overlying the shell opening.

9. The combination of a cylindrical shell rotatable about a generally horizontal axis, means at the interior surface of a portion of the shell forming two circumferential rows of air compartments, a circumferential partition separating the compartments of the two rows, said shell having a circumferential series of openings so positioned that one part of each opening lies to one side of said partition and the remaining part lies to the other side of the partition, a relatively stationary wind-box at least partly encircling the shell and having a discharge opening facing the shell and under which said shell openings are adapted to move, a hood for each of said shell openings projecting within the shell and substantially preventing passage of solid material from the air compartment into the wind-box but permitting passage of air from the wind-box into the air compartment, and adjustable means in said hood the relative proportions of air entering the compartments at opposite sides of said partition.

10. The combination of a rotatable cylindrical shell, a relatively stationary wind-box at least partly encircling the shell and having a circumferentially elongated discharge opening facing the shell, the shell having a series of openings adapted to move successively into registry with said discharge opening and through which air may pass from the wind-box into the interior of the shell, means for supporting the wind-box so that it is out of contact with the shell wall, and a seal for preventing escape of air from the wind-box to the atmosphere including a pair of members mounted on the shell to encircle the latter and lying on either side of the wind-box and means on the wind-box extending throughout the length of the latter and making seating contact with the members.

11. The combination of a rotatable cylindrical shell, a relatively stationary wind-box at least partly encircling the shell, said wind-box being channel-shaped in cross-section with the opening in the channel facing the wall of the shell, the shell having a series of openings adapted to move directly into registry with said opening in the wind-box and through which air may pass from the wind-box into the interior of the shell, means for supporting the wind-box so that it is out of contact with the shell wall, a pair of members secured to the shell and projecting radially outward and between which the wind-box is positioned, and an air seal positioned between each of said members and the adjacent lateral wall of the wind-box.

12. The combination of a rotatable cylindrical shell, means at the interior surface of a portion of the shell forming two circumferential rows of air compartments, a circumferential partition separating the compartments of one row from those of the other, said shell having a circumfer-

ential series of openings so positioned that one part of each opening lies at one side of said partition and the remaining part lies at the other side of said partition, a relatively stationary wind-box encircling at least part of the shell and having a discharge opening facing the shell, said shell openings coming successively into registry with said discharge opening as the shell rotates to permit air from the wind-box to flow through the shell openings and into said compartments, and adjustable means at each shell opening for varying the relative proportions of the quantities of air entering the compartments at opposite sides of said partition.

13. The combination of a rotating cylindrical shell, longitudinal and circumferential partitions mounted against the inner surface of a portion of a shell and forming at least one circumferential row of air compartments, a cover plate for each compartment, a pedestal secured to the shell in each compartment and lying in line with the central portion only of the cover plate, and means for clamping the central portion of the cover plate to said pedestal.

JOHN NARSTED.
POVL T. LINDHARD.

CERTIFICATE OF CORRECTION.

Patent No. 2,268,296.

December 30, 1941.

JOHN MARSTED, ET AL.

It is hereby certified that error appears in the printed specification of the above numbered patent requiring correction as follows: Page 5, second column, line 34, claim 9, after "hood" insert --for regulating--; and that the said Letters Patent should be read with this correction therein that the same may conform to the record of the case in the Patent Office.

Signed and sealed this 3rd day of March, A. D. 1942.

(Seal)

Henry Van Arsdale,
Acting Commissioner of Patents.
